George Browning

By *Alie O'Kee* Atty's

UNITED STATES PATENT OFFICE.

GEORGE BROWNING, OF CHICAGO, ILLINOIS.

SAFETY RAZOR.

Application filed January 20, 1920. Serial No. 352,665.

To all whom it may concern:

Be it known that I, GEORGE BROWNING, a subject of the King of England, residing at Chicago, in the county of Cook and State of Illinois, have invented certain new and useful Improvements in a Safety Razor, of which the following is a description:

My invention belongs to that general class of devices known as razors and especially to that class of razors more particularly known as safety razors and is of the type in which a reciprocating blade is mounted upon a suitable head or carrier. The invention has among its objects the production of a device of the kind described, that is simple, convenient, durable, attractive, efficient and satisfactory for use wherever found applicable. It has particularly as an object the production of an exceedingly simple construction of few parts, which will be particularly convenient in use. Many other objects and advantages of the construction herein shown and described will be obvious to those skilled in the art, from the disclosure herein given.

To this end my invention consists of the novel construction, arrangement and combination of parts herein shown and described and more particularly pointed out in the claims.

In the drawings, wherein like reference characters indicate like or corresponding parts.

Figure 1 is a front elevation of my improved device,

Figure 2 is a side elevation of the same,

Figure 3 is a sectional view taken substantially on line 3—3 of Figure 2,

Figure 4 is a sectional view taken substantially on line 4—4 of Figure 1,

Figure 5 is a plan view of the preferred form of blade; and

Figure 6 is a plan view of the preferred form of blade retaining member.

Referring to the drawings, my improved razor consists of a head plate or body part 1, preferably formed with an extending part 2 at the back edge, to which the handle 3 is secured, the handle being of the desired size and length, and, as shown, formed with knurled portion 4 so that the same may be

firmly grasped. The handle may be made detachable if desired. The body part of plate 1 is preferably formed with the extending parts or flanges 6—6 at each side of the part 2 in which are formed bearings for the roller 7. The roller 7 is provided with the supporting shaft or parts 5—5, one of which is formed with a bearing portion 8 at one end to engage the flange 6. The opposite end of the roller may be pivotally or rotatably supported at the adjacent flange 6 by means of a screw 9, or equivalent means for the purpose, having a portion engaging the end of the adjacent part 5. As shown, the roller 7 is formed with cam faces 10 at the ends for engagement with the cooperating blade, as hereafter set forth. I prefer to cut away the plate 1, as indicated at 12, in a series of notches so as to form the projecting parts or teeth 11 which come in contact with the face.

Carried by the plate 1, at preferred points, are the desired number of projecting lugs 15 which may be formed integrally with the plate or, as shown, inserted, the same projecting from the plate a distance slightly greater than the thickness of the blade. This is a detail in the construction which may be varied as found desirable. The blade consists of a plate 17 which is preferably substantially thin and formed with a cutting edge 18 and with slotted openings 19 of a size to fit the lugs 15. The blade 17 is, of course, constructed of a suitable material which will hold a cutting edge. The lugs or pins 15 and the openings 19 form an interengaging connection between the head and the blade that will permit the sliding or reciprocating of the blade 17 on the plate or head. The blade is cut away as at 20 and slightly cut back at 21 so as to form shoulders or prongs 22 which are arranged to engage with the cam faces 10 at the ends of the roller 7. As will be clear by referring to Figures 1 and 3, the cam faces 10 are oppositely formed so that as roller is rotated, the same engaging faces 21 on the blade causes the blade to be reciprocated back and forth lengthwise. The blade is maintained in place by a clamping member or plate 24 which, in the construction shown, is so

mounted on the device that it may be quickly and easily detached for removing or replacing of the blade at such times as may be desired. I have shown the clamping member 5 24 provided with notches as indicated at 25 so as to form the projecting prongs 26, the same being also preferably notched or cut away a sat 27. Mounted on the plate 1 and preferably extending substantially centrally 10 each of the lugs 15, is a pin or stem 29 which carries a head 28 arranged to overlie the plate 24 and retain the same in place, the plate resting or bearing upon the lugs 15. The stems 29 may be controlled in any suitable manner, preferably by means of springs 15 31, or the equivalent. In the construction shown, each of the springs 31 is arranged within a chambered part 30 secured on the stem and bears against the end of the chambered part and a filler member 32. The spring tends to maintain the stems 29 and the heads 28 so as to firmly secure the clamping plate 24 in place. The purpose of the filler block 32 is to so coorporate with the 20 25 chambered part 30 that the spring is entirely inclosed.

The operation of the device will be obvious. As the razor is drawn over the face, the roller 7 arranged at the back of the 30 blade contacts with the face and is rotated, thereby reciprocating the blade lengthwise at the same time the same is drawn transversely on the face. The result is a clean, close and comfortable shave without any 35 discomforts. The same also permits rapid shaving and permits the use of a safety razor by many who have heretofore been unable to shave with comfort with any type of safety razor. The razor being of but 40 few parts, its does not easily get out of order and is most convenient to use inasmuch as by sliding the clamping member to one side it may be easily detached and the blade may be removed for cleaning or 45 drying or for honing, stropping or the like, or a new blade may be inserted. All of the parts are easily accessible and consequently may be easily dried.

Having thus described my invention, it 50 is obvious that various immaterial modifications may be made in the same without departing from the spirit of my invention, hence I do not wish to be understood as limiting myself to the exact construction, arrangement, combination of parts or uses mentioned.

What I claim as new and desire to secure by Letters Patent is:

1. A razor comprising a handle, a head 55 mounted at one end of said handle and a longitudinally slidable blade mounted upon said head at the side opposite said handle, means for attaching said blade thereto, in combination with a roller mounted upon said head on the side adjacent to and beyond

said blade holder, said blade being engageable with said roller whereby the blade is reciprocated upon rotation of the roller.

2. In a razor of the kind described and in combination, a handle, a head mounted 70 at one end of said handle, comprising a substantially flat plate extending transversely thereof, a blade mounted upon said head at the side opposite said handle, means for slidably attaching said blade thereto, a 75 roller mounted upon said head on the side adjacent to and beyond said plate, said blade being engageable with said roller at the ends whereby the blade is reciprocated upon rotation of the roller. 80

3. In a razor of the kind described and in combination, a handle, a head mounted at one end of said handle comprising a substantially flat plate rigidly secured near the center of its length to said handle, and 85 extending transversely thereof, a longitudinally slidable blade mounted upon said head at the side opposite said handle, means for detachably securing said blade thereto, a 90 roller mounted upon said head on the side adjacent to and beyond said blade holder and constructed with means for directly contacting with and engaging said blade, whereby upon rotation of the roller the 95 blade is reciprocated. 95

4. In a razor of the kind described and in combination, a handle, a head mounted at one end of said handle, a blade mounted upon said head at the side opposite said handle, a clamping member secured to the head adjacent one end of said blade and of a length to overlie the blade, and engage with the head adjacent the opposite end of the blade, means carried by said head and cooperating with said clamping member for maintaining the blade on said head, a roller mounted upon said head and directly engaging said blade at its ends, whereby the blade is reciprocated upon rotation of the 100 105 roller. 110

5. A razor comprising a handle, a head mounted at one end of said handle, a blade mounted upon said head at the side opposite said handle, interengaging means between said head and blade whereby the 115 blade is slid able on the head, means cooperating with said interengaging means for preventing displacement of the blade, a roller mounted on said head and provided with cam faces at each end, and means on and integral with said blade for engaging said cam faces whereby the blade is reciprocated upon rotation of the roller. 120

6. In a device of the kind described and in combination, a handle, a head mounted at 125 one end of said handle, comprising a substantially flat plate rigidly secured near the center of its length to said handle and extending transversely thereof, with a longitudinally slid able blade mounted upon 130

- 5 said head at the side opposite said handle, provided with slots therein, pins projecting from said head and engaging said blades in said slots, means for securing said 5 blade in place on the head and in engagement with said pins, a roller mounted upon said head at the rear of said blade and having cam faces at each of its ends, and means upon and integral with the blade at each 10 end thereof for engaging said cam faces on said roller whereby upon rotation of the roller the blade is reciprocated.
- 10 7. A one-piece safety razor blade consisting of a thin plate provided with a cutting 15 edge at one side and with a projection at each end of the opposite side forming cam surfaces whereby the blade may be reciprocated, said plate having apertures therein intermediate said sides.
- 15 8. A one-piece safety razor blade consisting of a thin plate formed with a cutting edge at one side and cut away at the opposite side to provide a projecting part adjacent each end forming cam surfaces 20 whereby the blade may be reciprocated, said plate being apertured intermediate said sides.
- 20 9. In a razor of the kind described and in combination, a handle, a head mounted at one end of said handle, a blade mounted upon said head at the side opposite said handle, interengaging means between the said head and blade whereby the blade is 25 slidable on the head, a plate mounted on said blade, means for maintaining said plate in place, a roller mounted on said head at the rear end of said blade and arranged at its ends to engage directly with the blade whereby the blade is reciprocated upon 30 rotation of the roller.
- 30 10. In a razor of the kind described and in combination, a handle, a head mounted at one end of said handle, a blade mounted upon said head at the side opposite said handle, interengaging means between the said head and blade whereby the blade is 35 slidable on the head, a plate mounted on the said blade, means for maintaining said plate in place including means projecting through 40 the head and the blade and engaging outer face of the said plate, a roller mounted on said head at the rear edge of said blade and arranged at its ends to engage with the blade whereby the blade is reciprocated upon 45 rotation of the roller.
- 45 11. In a razor of the kind described and in combination, a handle, a head mounted at one end of said handle comprising a substantially flat plate rigidly secured to said 50 handle and extending transversely thereof, with a longitudinally slidable blade mounted upon said head at the side opposite said handle, said blade provided with slots therein, pins projecting from said head, sleeves 55 on said pins and projecting beyond said head plate a distance slightly greater than the thickness of said plate and engaging said blades in said slots, means for securing said plate in place on the head and in engagement with said pins and the outer ends of said sleeves, a roller mounted upon said head at the rear of said blade, and having means at its ends for directly engaging said blade, whereby upon rotation of the roller the blade is reciprocated. 75
- 75 12. In a device of the kind described and in combination, a handle, a head mounted at one end of said handle comprising a substantially flat head plate rigidly secured to and extending transversely thereof, with a longitudinally slidable blade mounted upon said head at the side opposite said handle and provided with slots therein, yieldable pins projecting from said head plate, sleeves on said pins, said sleeves projecting beyond said head plate a distance slightly greater than the thickness of said blade and engaging said blades in said slots, means for securing said plate in place on the head and in yieldable engagement with said pins and 80 the outer ends of said sleeves, and a roller mounted upon said head at the rear of said blade and having cam faces at each of its ends, and means upon and integral with the blade at each end thereof for engaging said cam faces in said roller, whereby upon rotation of the roller the blade is reciprocated. 85
- 85 13. In a razor of the kind described and in combination, a flat head plate having a handle extending therefrom, a blade adapted to have reciprocatory sliding movement along the head plate, means detachably secured to the head plate for maintaining the blade upon the head plate while permitting the same to reciprocate relatively to the head plate, a rotatable roller on the head plate located at one side thereof adjacent the rear edge of the blade, said roller directly engaging said blade to reciprocate it. 90
- 90 14. In a razor of the kind described and in combination, a flat head plate having a handle extending therefrom, a blade adapted to have reciprocatory sliding movement along the head plate, means detachably secured to the head plate for maintaining the blade upon the head plate while permitting the same to reciprocate relatively to the head plate, a rotatable roller on the head plate located at one side thereof adjacent to the rear edge of the blade, and a cam on said 100 roller directly engageable with said blade to reciprocate it. 105
- 100 15. In a razor of the kind described and in combination, a flat head plate having a handle extending therefrom, a blade adapted to have reciprocatory sliding movement along the head plate, said blade having an integral projection thereon, means detachably secured to the head plate for maintaining the blade upon the head plate while 110 115 120 125 130

permitting the same to reciprocate relatively to the head plate, a rotatable roller on the head plate located at one side thereof adjacent the rear edge of the blade, and a cam on said roller directly engageable with said projection reciprocated by said blade when said roller is rotated.

In testimony whereof, I have hereunto signed my name in the presence of two subscribing witnesses:

GEORGE BROWNING.
